UNITED STATES PATENT OFFICE.

ISRAEL A. ANTOPOL, OF BROOKLYN, NEW YORK.

EMBROIDERING-MACHINE.

1,031,681.

Specification of Letters Patent.

Patented July 9, 1912.

Application filed January 14, 1911. Serial No. 602,576.

To all whom it may concern:

Be it known that I, ISRAEL A. ANTOPOL, a citizen of the United States, and a resident of the borough of Brooklyn, in the county of Kings and State of New York, have invented certain new and useful Improvements in Embroidering-Machines, of which the following is a specification.

My invention relates to embroidering machines, and has for its principal object to provide in machines of this character, mechanism for sewing with invisible stitches, a cord, piping or braid onto the material to be embroidered, and at the same time, twisting a thread or cord about said first mentioned cord, piping or braid, while the latter is being sewed onto the material.

A further object of this invention is to provide means for varying the spacing of the convolutions of the thread or cord, as it is being wound about the other cord.

A still further object of this invention is to provide means whereby the reel carrying the thread or cord may be rewound without taking it off from the machine.

Other objects will appear from the detailed description, and will be more definitely pointed out in the accompanying claims.

In the drawing illustrating this invention: Figure 1 is an elevation, partly in section, of an embroidering machine, with my invention applied thereto. Fig. 2 is an elevation partly cut away, illustrating the means I provide for rewinding the reel carrying the thread or cord. Fig. 3 is a plan illustrating diagrammatically the speed-changing gearing for varying the spacing of the convolutions of the thread or cord. Fig. 4 is an elevation of the mechanism illustrated in Fig. 3. Figs. 5, 6, 7 and 8 illustrate the reel and the method of its mounting. Fig. 9 is a sectional detail view, on an enlarged scale, taken along line a in Fig. 1.

1 indicates the needle shaft which is driven by pulley 2 and operating needle-bar 3 in the usual manner. Spool 4 carries thread 5, which runs through needle 6 on the needle-bar, to form the ordinary lock-stitch. Mounted on the same bracket with spool 4 is a spool 7 carrying a cord, piping or braid 8, which is threaded through the opening through which the needle-bar passes, and is then guided by guiding member 9, so as to present the under side of the cord to the needle, as illustrated in Fig. 9.

The guiding member 9 has a lateral opening 10, through which the cord enters, and an additional opening 11, through which the cord passes out again, forming a loop, the apex of which projects in opening 12, through which the needle passes. It will be seen that as the material 13 and the cord are fed along, the stitching which engages only the under side of the cord, will be concealed. I illustrate the lower thread 14 of the lock-stitch, but the mechanism below the table is omitted for the sake of clearness. The stitching is omitted in Fig. 1, and the windings of the thread about the cord are omitted in Fig. 9, for the same reason. It will be understood that any mechanism for producing a lock-stitch may be used in connection with my improved machine.

Projecting from the arm of the machine, is a bracket 15, having a depending tubular bearing or sleeve 16, on which is mounted a sleeve 17 having a gear-wheel 18 at one end, and a threaded portion 19 at its other end. Reel 20 is mounted on the sleeve and is held in position by nut 21, which engages the threaded portion 19 of sleeve 17. This reel is provided at its upper end with a gear-wheel 22, the purpose of which will be hereinafter described. Reel 20 carries the thread or cord 23 which is to be wound around cord, braid or piping 8. This thread or cord is guided in a bracket 24, which is attached to the nut 21, and an extension 25 fastened to the bracket. The reel is frictionally held to sleeve 17 by a spring 26 which is pressed against it by a screw 27, threaded in the nut 21. When the gear 18 is rotated, the reel is frictionally carried along with it, and the thread 23 is wound around the cord 8. Gear 18 is driven from needle shaft 1 as follows: Fixed to the needle shaft is gear 28 which drives the pulley shaft 29 through gear 30. The motion of this last shaft is transmitted by bevel gears 31 to shaft 32 which has mounted thereon a gear 33, having several rows of teeth of varying diameters, each of which rows may be brought into driving engagement with an idler gear 34, mounted on a pin adjustable in slot 35. This idler transmits its motion to gear 18 through a second idler 36. All of this gearing which transmits the motion from the gear 28 to gear 18 is mounted in a bracket 37 and an extension 38, projecting laterally from this bracket. When it is desired to change the spacing of the convolutions of the thread, idler 34 is

loosened and moved out of engagement with the gears 33 and 36. Gear 33 is then loosened from its shaft and slid along until its proper row of teeth is brought into alignment with gear 34. The latter is then adjusted in the engagement with gears 33 and 36 and then made fast axially to its support.

When it is desired to rewind the reel 20, a bracket 39 is attached to the under side 10 of extension 38 by means of pins or screws 40. Mounted in this bracket is a gear 41 which meshes with gear 22 on the reel. The latter can then be turned manually by crank 42, shaft 43 and gear 44 and 45.

15 With my improved machine, as above described, a cord, piping or braid can be embroidered on material, and another cord or thread can be wound around it with a considerable space between the convolutions, 20 and still no stitching will be seen on account of the manner in which the cord is sewed on to the material. The thread can be of different color from the cord on which it is wound, and thus a highly ornamental effect 25 is obtained. I preferably employ a lock stitch for sewing the cord on to the material in order to prevent the customary ravelling accompanying the use of the chain stitch. The lock stitch is also preferable for 30 the reason that it takes better hold of the material than the ordinary forms of chain stitch. However, it is obvious that any form of stitch may be used without departing from the spirit of this invention.

35 It will be noted that the reel containing the thread can be rewound without its being removed from its position on the machine. This saves a great deal of time and labor. The concentric mounting of this 40 reel renders the whole structure compact, and makes it possible to use a larger reel without taking up too much space. Moreover, danger of hitting the operator, which is present in machines of this character containing eccentrically mounted wheels, is 45 avoided.

Where the term cord is used in the claims, it is contemplated to designate generally, cord, piping or braid.

50 I claim:

1. In an embroidering machine, a cord guide having an opening through which the cord passes, said opening guiding the cord so as to present the under side of the cord 55 to the needle, stitch forming mechanism for sewing said under side of the cord to the material, mechanism for winding a thread or cord around the first mentioned cord or cord while the latter is being sewed onto the 60 material and means for varying the spacing of the convolutions of said winding thread or cord.

2. In an embroidering machine, a cord guide having an opening through which the cord passes, said opening guiding the cord 65 so as to present the under side of the cord to the needle, a needle shaft, a needle bar, stitch forming mechanism for sewing said under side of the cord to the material, mechanism for winding a thread or cord around 70 the first mentioned cord while the latter is being sewed onto the material, said mechanism comprising a reel mounted concentrically with the needle bar and driven from the needle shaft, and means for varying the 75 spacing of the convolutions of said winding thread or cord.

3. In an embroidering machine, a needle bar, a cord guide for guiding a cord to be sewed onto the material, mechanism for 80 winding a thread or cord about said first mentioned cord while the latter is being sewed onto the material, said mechanism comprising a reel mounted concentrically with the needle bar, tension means for said 85 reel and means for sewing to the material, the under side of the first mentioned cord.

4. In an embroidering machine, a needle bar, means for twisting a thread about a cord while the latter is being sewed onto 90 the material, said means comprising a reel mounted concentrically with the needle bar, a gear attached to the reel and means for rotating said gear to rewind the reel.

5. In an embroidering machine, a needle 95 bar, means for twisting a thread about a cord while the latter is being sewed onto the material, said means comprising a reel mounted concentrically with the needle bar, a gear attached to the reel, and detachable, 100 manually operable means for rotating said gear to rewind the reel.

6. In an embroidering machine, a needle shaft, a needle bar, mechanism for winding a thread about a cord while the latter is 105 being sewed onto the material, said mechanism comprising a sleeve, mounted concentrically with the needle bar, a gear on said sleeve, a bracket, a system of gearing mounted on said bracket for driving said sleeve 110 from the needle shaft, said system including a plurality of change speed gears longitudinally slid able and an idler gear between said slid able gears and the gear on the sleeve, said idler being adjustable laterally 115 to accommodate itself to the varying sizes of change speed gears.

Signed at New York in the county of New York and State of New York this 27th day of December A. D. 1910.

ISRAEL A. ANTOPOL.
